GASKET FOR INTERNAL COMBUSTION ENGINES

Arthur F. Gobb, Wyandotte, Mich., assignor to
McCord Radiator & Mfg. Co., Detroit, Mich., a
corporation of Maine

Application September 29, 1934, Serial No. 746,044

9 Claims. (Cl. 288—1)

This invention relates to internal combustion engines and particularly to a gasket structure adaptable for use therewith.

In many gasket installations one of the gasket functions is to prevent heat transfer between the elements which are connected by the gasket. For example, in modern internal combustion engines it has become a problem to prevent the conduction of heat from the intake manifold to the carburetor. It is highly necessary to prevent such heat transfer, as by a gasket, in view of the vapor-lock difficulties encountered if the gasoline in the carburetor attains its boiling temperature.

Another function performed by gaskets, particularly by the gasket placed between the carburetor and the intake manifold, is to support the weight of the carburetor and of the air cleaner if one is used. Consequently any gasket structure which may here be used must have, in addition to very good insulating properties, sufficient structural strength to withstand the loads imposed thereon by the carburetor. The scope of the problem becomes well understood when it is realized that the best heat insulating materials are relatively weak structurally.

One of the objects of this invention therefore is to provide a load bearing gasket having abnormally high heat insulating qualities.

Another object of this invention is to provide means for ventilating a gasket structure.

A still further object of this invention is to provide an internal combustion engine structure in which the engine fan stream serves to circulate air through ventilating ducts provided in a gasket located within the fan stream.

Other objects of the invention will appear from the following description taken in connection with the drawing, which forms a part of this specification, and in which:

40 Fig. 1 is a side elevational view of an internal combustion engine equipped with a gasket structure incorporating my invention;

45 Fig. 2 is an enlarged view in elevation of a portion of the internal combustion engine shown in Fig. 1, taken on the line 2—2 thereof;

Fig. 3 is a sectional view taken on the line 3—3 of Fig. 2;

Fig. 4 is a sectional view taken on the line 4—4 of Fig. 2;

50 Fig. 5 is a sectional view taken on the line 5—5 of Fig. 3, and

Fig. 6 is a sectional view of a modification of the gasket structure shown in Fig. 2, the section being taken on a line corresponding to the line 55 3—3 of Fig. 2.

Referring to Fig. 1, 10 illustrates a conventional internal combustion engine having an intake manifold 11 fitted with a hot spot 12 connected to the exhaust system 13. The intake manifold is joined to a carburetor 16 fitted with an air cleaner 17. The carburetor and intake manifold are flanged as at 18 and 19 respectively, these flanges being connected in a gas tight relationship by a gasket 21.

The engine cooling system, which includes an engine driven fan 22 creates a blast of air the temperature of which is lower than that of the manifold. This air flowing rearwardly over the engine serves to cool the gasket 21 due to the fact that the gasket is located within the air stream.

The gasket is made of suitable gasket material which may be asbestos, reinforced as in the patent to Bailey, 1,968,365, issued July 31, 1934, or other heat insulating material having sufficient structural strength. As shown the gasket is made of a plurality of layers of asbestos. These layers each contain a centrally located hole, which in the completed gasket provides the gas passage 23. Each layer of asbestos is also punched to provide a pair of bolt holes 24. The several layers of asbestos may be bound together in any desired manner.

The central gas passage 23 may be lined with a cylindrical ring 26, made of a suitable smooth material, such as metal, in order to present a minimum of resistance to gas flow. As shown this ring extends axially of the passage 23 throughout a major portion of its length, and is crimped at its ends into the body of the gasket as at 27 and 28, being thus located within the gasket 35 in order to avoid contact with the adjacent flanges 18 or 19. In this way heat conduction is still further minimized.

In order removably to join the two flanges, bolts 29 are inserted through the holes 24. As shown these may threaded engage the flange 19. It will be noted that a washer 31 may be inserted between the flange 18 and the heads of the bolts still further to reduce the conduction of heat from the hot manifold to the carburetor. A slight clearance exists between the shanks of the bolts 29 and the carburetor flange 18 and therefore heat can flow between these two parts only with difficulty.

It will further be noted that each of the flanges supports the gasket 21 over an area sufficiently large to carry not only the bolt load but also the weight of the carburetor and the air cleaner.

In detail, the gasket comprises a plurality of layers 32 of asbestos material each having iden- 55

tical cut-out portions 34 and 36 extending inwardly from the exposed or non-bearing faces of the gasket. In stacking these identical layers alternate ones are turned upside down, the cut-out portions of adjacent layers thus overlapping to form passage-ways or ducts 37, 38 extending axially of the gasket, between the central opening 23 and the bolt holes 24. The remainder of the cut-out portions together with the adjacent layers which are not cut out, form ducts extending parallel to the bearing faces of the gasket and leading from the central ducts 37 and 38 to the exposed or non-bearing faces of the gasket. Thus the gasket structure is honey-combed with 15 passageways communicating with the atmosphere at several points.

The open ends of the ducts lie, it will be noted in Fig. 1, in the air stream flowing rearwardly from the fan 22. The air stream thus tends to 20 increase the circulation of air through the body of the gasket and any heat which may be conducted into the gasket from the hot manifold flange 19 is removed therefrom before it can reach the cooler carburetor flange 18.

25 A layer of gasket material 38' in which no cut-out portions have been formed may be placed on top and even on the bottom of the gasket and bound thereto in any convenient manner as by the flange on the cylinder 26. This will 30 serve to close the ends of the ducts 37 and 38 and keep them free from any dirt which might otherwise collect either during the handling or shipping of the gasket.

The structure illustrated in Fig. 6 is identical 35 with that illustrated in Fig. 2 except for the cut-out portions. In Fig. 6 it will be noted that, in each layer, there is a pair of slots or cut-out portions 39 and 41 lying between the opening 23 and the bolt holes 24. In the assembled gasket 40 these extend from one side of the center line to the opposite exposed or non-bearing faces. When layers cut out in this manner are stacked with alternate layers turned upside down, it will be noted that a pair of ducts 42 and 43 extend axial- 45 ly of the gasket in a manner similar to ducts 37 and 38.

Each layer of the modification shown in Fig. 6 also contains a pair of circumferentially extending slots 44 and 46 which in the assembled gasket 50 substantially surround the aperture 23.

In the assembled structure there is thus a passageway completely around the aperture 23, the passageway being composed of slots in alternate 55 layers of the gasket material and comprising, for example, the slot 44, the slot 46, the cut-out portion 39 communicating with the axially extending duct 43, the cut-out portion 39 in the adjacent layer, the slot 46 and the slot 44, the slot 41, the axial duct 42, and the cut-out portion 41 back 60 to the slot 44. Thus no matter how the gasket is located with respect to the air stream, one or more of the ducts extending through to the exposed faces of the gasket are bound to receive a portion of the air stream and ventilate the gasket.

65 While I have herein described in some detail a specific embodiment of my invention, which I deem to be new and advantageous and may

specifically claim, I do not desire it to be understood that my invention is limited to the exact details of the construction, as it will be apparent that changes may be made therein without departing from the spirit or scope of my invention. 5

Having thus described my invention, what I claim and desire to secure by Letters Patent is:

1. In a gasket, a plurality of sheets of gasket material, each of said sheets having cut-out portions therein, said portions being so arranged 10 and said sheets being so superimposed as to form a plurality of passageways through the body of said gasket substantially parallel to a bearing face thereof.

2. A gasket comprising a plurality of sheets 15 having identical cut-out portions, said sheets being alternately arranged whereby said cut-out portions overlap to form a passageway within the body of the gasket perpendicular to the bearing faces thereof, and a plurality of ducts substantially perpendicular to said passageway.

3. In a gasket having a central aperture, a plurality of circumferentially extending interconnected ducts within said gasket forming a 20 passageway substantially surrounding said aperture and exposed to the atmosphere.

4. In a gasket having a central aperture, a circumferentially extending passageway substantially surrounding said aperture and in communication with the atmosphere, said passageway comprising a plurality of overlapping ducts lying 30 in adjacent planes.

5. A gasket comprising identical superposed 35 layers of gasket material, each layer having identical cut-out portions therein extending to an edge thereof, the adjacent layers of said gasket being superposed with said cut-out portions extending alternately in opposite directions.

6. A gasket comprising identical superposed 40 layers of gasket material, each layer having identical cut-out portions therein extending to an edge thereof, said cut-out portions in adjacent layers being overlapped in the assembled gasket to form an irregular passageway through said 45 gasket.

7. In a gasket body having a bearing face, a plurality of intersecting passageways in said body, at least one of said passageways lying at an angle to a bearing face of said gasket, and at least 50 one of said passageways being in communication with the atmosphere.

8. In a multiple layer gasket, apertures in adjacent layers, said apertures being superposed to form a continuous passageway through said gasket, a slot in each of said layers, said slots being superposed and extending in opposite directions from said continuous passageway whereby to form 55 a plurality of irregular passageways intersecting said continuous passageway.

9. A gasket having an aperture therethrough, the body of said gasket having a plurality of intersecting bores therein, said bores cooperating to form a passageway extending circumferentially 60 of said aperture.

65 ARTHUR F. GOBB.
